TAPE FOR SLIDE FASTENERS

David Silberman, New York, N. Y., assignor to
Ideal Fastener Corporation, New York, N. Y.,
a corporation of New York

Application April 21, 1936, Serial No. 75,513

4 Claims. (Cl. 139—384)

This invention relates to improvements in tapes or stringers, applied in conjunction with separable slide fastener closures, being specifically directed to a woven tape, the cord or bead 5 of which is disposed intermediate the edges of the tape or stringer.

Broadly, it is an object of this invention to provide for a tape or stringer applied in conjunction with separable slide fasteners, which 10 tape comprises a woven material intermediate the edges of which there is inserted in the place of certain of the warp threads a cord or bead, which element is interlocked with the tape or stringer by the weft threads encircling the peripheral surfaces of the same.

Specifically, it is an object of this invention to provide a tape or stringer for separable slide fasteners, wherein there is woven into the tape intermediate its edges, in the place of certain of 20 the warp threads, a cord or bead of dimensions considerably greater than the thickness of the tape, the cord or bead providing a bulge or projection of equal depth on opposite sides of the tape or, if desired, of small bulge on one side and 25 a considerably greater bulge on the other, the weft being woven so that alternate threads surround the same peripheral sections of the bead or cord and adjacent threads surround opposite peripheral sections of the bead or cord.

Still further, it is an object of this invention 30 to provide for a woven tape for separable slide fasteners, comprising a woven element, into which there is interlocked intermediate of its ends, in lieu of certain warp threads, a bead, the bead being adapted to be clamped by the jaws of a fastener, the portion of the tape on one side of the bead serving to fasten the unit to the device to which it is applied, and the section of the tape on the other side of the bead serving 35 to form a cover for the head of the fastener elements, thereby to provide for the formation of a covered slide fastener.

These and other advantages, capabilities and features of the invention will appear from the 40 subjoined detailed description of one specific embodiment thereof illustrated in the accompanying drawing, in which

Figure 1 is a plan view of the covered separable fastener.

Figure 2 is a perspective view of one side of the covered separable fastener, showing one of the embodiments of the fastener tape.

Figure 3 is a plan view of the fastener tape.

Figure 4 is a front elevation in section, taken 45 along lines 4—4 of Figure 3.

Figure 5 is a plan view of a modified form of fastener tape.

Figure 6 is a front elevation in section, taken along lines 6—6 of Figure 5.

Figure 7 is a perspective view of the fastener tape shown in Figures 5 and 6 as associated with a fastener element.

Referring to the reference characters in the drawing, numeral 10 represents a slide fastener assembly of the type specified, wherein series 11 10 and 12 of mating fastener elements are disposed in alternation on tapes 13 and 14, slide 15 serving to seal or open the closure formed by separable fastener elements by reciprocation in a manner well known to the art.

Referring specifically to Figures 2, 3 and 4, there is shown a woven tape 20, intermediate the ends of which is disposed, in lieu of certain warp threads, a bead or cord 21, in this case, of cylindrical formation, said bead being interlocked between parallel series of weft cords 22 and 23, the cords 22 being normally adjacent cords 23, the alternate cords 22 being parallel and surrounding the same surface 24 of the bead, while intervening weft cords 23 surround the same peripheral surface 25 of the cord or bead 21.

In the particular modification shown in Figures 2 to 4, the cord 21 is disposed so that it projects or bulges substantially away from the lower face of the tape 20 in contradistinction to the slight or unappreciable bulge towards the upper face of tape 20.

As indicated in Figure 2, the cord or bead 21 separates the tapes into two parts, the fastening portion 26 and the covering portion 27. In 35 assembly of the fasteners upon the tape, the tape is placed in flatwise manner over the top 28 of the fastener element 11, so that the bead or cord portion thereof depends into groove 29 between jaws 30 of the fastener. Upon clamping of the 40 jaws to position shown in Figure 2, the tape, particularly the bead portion thereof, is enclosed completely within the slot 29 and the edges 31 of the jaws 30 press against sections of the tape adjacent the bead to firmly clamp such 45 portions 32, thus locking the fastener to the tape with the fastening attachment and fastener head cover portions 26 and 27 of the tape 20 resting flatwise and substantially in one plane on the flat surface 28 of the fastener.

Referring to the modification shown in Figures 5 to 7 inclusive, the bead 41 carried in the tape 40 replaces certain of the warp threads intermediate of its edges, but in this instance, the bead 41, which is cylindrical in form, is disposed 55

so that it bulges equally from both faces of the tape, and the adjacent weft threads 42 and 43 surround opposite semi-circular peripheral surfaces of the bead or cord and are of substantially the same length, the alternate weft threads being parallel to one another and passing in the same direction.

As shown in Figure 7, the length of the portions in the fastener attachment and fastener head cover portions 44 and 45, adjacent the bead 41, which are clamped by the jaws 30 of the fastener 11, are much greater than that clasped in the other embodiment described, but the clamping action of the jaws and the neck formation produced thereby is similar in nature, the fastener attachment surface 44 and fastener head cover surface 45 of the tape, after the clamping of the bead 41 by the jaws of the fastener, resting on upper flat surface 28 of the fastener, to produce substantially the same effect as that shown in the previous embodiment.

It is obvious that various changes and modifications may be made to the details of construction without departing from the general spirit of the invention as set forth in the appended claims.

I claim:

1. A scoop-carrying tape for interlocking scoop type slide fasteners, consisting of a series of generally parallel warp threads of relatively small cross-section, a single unbent anchorage warp thread of relatively large cross-section adjacent thereto and extending in a straight line, a second series of generally parallel warp threads adjacent said anchorage-warp thread, the warp threads of said second series being generally equal in cross-section to the warp threads of said first series and lying on the opposite side of said anchorage warp thread, said second series having relatively fewer warp threads than the first series, and a weft thread interlaced generally equally with all the warp threads to unite them into a unitary fabric structure.

2. A scoop carrying tape for interlocking scoop type fasteners consisting of an integrally woven structure formed of generally parallel body warp threads of generally equal cross-section and a single unbent anchorage-warp thread of rela-

tively large cross-section spaced substantially nearer to one of the marginal body-warp threads than to the other marginal body-warp thread and extending in a straight line, and a weft thread interlaced with all of said body-warp threads and with said anchorage-warp thread at each traverse thereof to form a unitary structure having the anchorage-warp thread firmly bound in and having the selvage edges at said marginal body-warp threads.

3. A scoop-carrying tape for interlocking scoop type slide fasteners, consisting of a series of generally parallel warp threads of relatively small cross-section, a single unbent anchorage warp thread of relatively large cross-section adjacent thereto and extending in a straight line, a second series of generally parallel warp threads adjacent said anchorage-warp thread, the warp threads of said second series being generally equal in cross-section to the warp threads of said first series and lying on the opposite side of said anchorage warp thread, said second series having relatively fewer warp threads than the first series, and a weft thread interlaced generally equally with all the warp threads to unite them into a unitary fabric structure, such anchorage thread being positioned in the tape to be disposed at one face and largely disposed beyond the other face of said tape.

4. A scoop-carrying tape for interlocking scoop type fasteners consisting of an integrally woven structure formed of generally parallel body warp threads of generally equal cross-section and a single unbent anchorage warp thread of relatively large cross-section spaced substantially nearer to one of the marginal body-warp threads than to the other marginal body-warp thread and extending in a straight line, and a weft thread interlaced with all of said body-warp threads and with said anchorage-warp thread at each traverse thereof to form a unitary structure having the anchorage-warp thread firmly bound in and having the selvage edges at said marginal body-warp threads, such anchorage thread being positioned in the tape to be disposed at one face and largely disposed beyond the other face of said tape.

DAVID SILBERMAN.
